(57) **CLAIM**

The ornamental design for a brush holder, as shown and described.

DESCRIPTION

FIG. 1 is a front elevational view of my new design;
 FIG. 2 is a rear elevational view thereof;
 FIG. 3 is a left side view thereof;
 FIG. 4 is a right side view thereof;
 FIG. 5 is a bottom plan view thereof;
 FIG. 6 is a top plan view thereof;
 FIG. 7 is a perspective view thereof;
 FIG. 8 is another perspective view thereof;
 FIG. 9 is the same perspective view as FIG. 7 showing a suction cup in broken lines; and,
 FIG. 10 is the same perspective view as FIG. 8 showing the suction cup and brush in broken lines.
 The broken line showing of a suction cup and a brush in FIGS. 9 and 10 illustrate environmental matters which form no part of the claimed design.
